UNITED STATES PATENT OFFICE

2,191,758

FLOAT SWITCH

George W. Heindel, York, Pa.

Application April 12, 1938, Serial No. 201,641

1 Claim. (Cl. 200—84)

My invention relates generally to means for warning of a full condition of a tank, and particularly to an arrangement especially applicable to the fuel tank of an oil burner, and operating for the purpose of warning the driver of the fuel oil supply truck at a distance from the tank that the tank is full, thereby eliminating the necessity on the part of the fuel truck driver of approaching the tank itself and observing the depth of the fuel therein, and an important object of my invention is to provide a simple and efficient arrangement of this character which can be easily installed in existing oil burner tank arrangements and the like.

Other important objects of my invention will be apparent from a reading of the following description taken in connection with the drawings, wherein for purposes of illustration I have shown a preferred embodiment of my invention.

In the drawings:

Figure 1 is a general longitudinal sectional view taken through a portion of a building and showing a fuel oil tank installed therein and equipped in accordance with the present invention.

Figure 2 is a wiring diagram.

Figure 3 is an enlarged longitudinal vertical sectional view taken through the upper part of the tank and through the float operated switch mechanism.

Figure 4 is a horizontal sectional view taken through Figure 3 approximately on the line 4—4 and looking downwardly in the direction of the arrows.

Figure 5 is a transverse vertical sectional view taken through Figure 3 approximately on the line 5—5 and looking toward the right in the direction of the arrows.

Referring in detail to the drawings, the numeral 5 generally designates the basement of a building having a wall 6 projecting above the ground 7, and the numerals 8 and 9 designate respectively a filling pipe and a vent extending through the wall 6 for convenient use of the driver of the fuel oil supply truck. In addition there is mounted on the exterior of the wall 6 and readily accessible to the said driver without approaching the tank 10 a mounting 11 comprising a bell or buzzer 12 and a hand switch 13. A suitable conduit 14 is passed through the wall 6 to bring the necessary conductors to the alarm 12 and the hand switch 13 and this conduit 14 extends to the float switch 15 which is mounted on the tank 10 within the building. It is obvious that the filling pipe 8, the vent 9, and the electrical conduit 14 may be extended to any

desirable length, to enable bringing them to an exterior point on the building readily accessible to the driver of the fuel truck.

The fuel tank 10 may be of any desirable form and has in its top a threaded opening 16 surrounded by a washer 17 through both of which is threaded a portion 18 on the float tube 19 which has above the washer 17 an annular boss 20 and below the tank top 21 a bottom 22 provided with an opening 23. The float tube 19 extends above the boss 20 and merges into the bottom of a casing 24. A preferably cylindrical float 25 operates in the float tube 19 and when the fuel within the tank reaches the full level, the rounded upper end 26 of the float 25 moves up into the casing 24 and engages and raises the plate 27 which is secured to the lower end of one arm of the beam 28 which is pivoted intermediate its ends as indicated by the numeral 29 to and between ears 30, 31 on a U-shaped support 32, the said beam 28 being of conductive character and the arm 28 thereof being adapted to be normally depressed by gravity when not engaged by the float 25. When the tank 10 is full the float will push the beam 28 up into engagement with the contact 34 which includes a threaded shank 35 passing through and insulated from an opening 36 in the removable top 37 of the casing 24, the said shank being insulated by the insulating block 38, and a nut 39 is threaded on the shank 35 to clamp the contact in place on the cover 37. A wire 40 leads from the contact 34, as indicated in Figure 2 to the arm 41 of the manual switch 13 whose opposite side is connected as indicated by the numeral 42 to one side of the bell or buzzer 43, whose opposite side is connected by the wire 44 to one output terminal of a transformer 45 or other suitable source of low voltage current. The opposite terminal of the transformer 45 is connected by a wire 46 to the pivot 29 of the beam 28, the wire 46 being led into the casing through a grommet equipped opening 47. Suitable wires 48 leading from a house current supply energize the transformer 45.

The U-shaped beam support 32 includes at the end thereof adjacent the float the inturned horizontal arms 49 which act as stops to prevent the beam 28 from falling too far downwardly, although these arms permit the beam 28 to fall sufficiently away from the contact 34 to break the circuit which is established when the beam engages the contact 34.

Although I have shown and described herein a preferred embodiment of my invention, it is to be definitely understood that I do not desire to

limit the application of the invention thereto, and any change or changes may be made in the structure and arrangement of the parts, within the spirit of the invention and the scope of the subjoined claim.

Having described the invention, what is claimed as new is:

10 A float operated switch comprising a casing, a substantially U-shaped bracket having its bight connected with an intermediate part of the bottom of the casing, an elongated flat switch arm having an intermediate part thereof pivoted between the limbs of the bracket adjacent the upper end of the bracket, each limb having a forwardly 15 extending part, the upper end of which is bent over, said bent over portions forming stops for limiting downward movement of the front end of

the arm, said front end of the arm being of greater weight than the rear portion whereby said front portion tends to drop by gravity and to normally rest upon the bent portions, a contact member passing through a hole in the top of the 5 casing and insulated from said top and having a portion adapted to be engaged by the front part of the switch arm when the arm is raised, a tubular part depending from the bottom of the casing and adapted to enter a tank, the bottom 10 of the tubular part having an opening therein for the admission of liquid from the tank into the tubular part and an elongated tubular float in the tubular part having its upper end adapted to engage the switch arm, to raise the same against 15 the contact, when the float is raised.

GEORGE WM. HEINDEL.
